(57) **CLAIM**

The ornamental design for a docking station for cleaning robot as shown and described.

DESCRIPTION

Docking station for cleaning robot

Reproduction 1.1 is a front view of a first docking station for cleaning robot, showing our new design;

Reproduction 1.2 is a back view thereof;

Reproduction 1.3 is a left view thereof;

Reproduction 1.4 is a right view thereof;

Reproduction 1.5 is a top view thereof;

Reproduction 1.6 is a bottom view thereof;

Reproduction 1.7 is a front perspective view thereof;

Reproduction 1.8 is a back perspective view thereof;

Reproduction 2.1 is a front view of a second docking station for cleaning robot, showing our new design;

Reproduction 2.2 is a back view thereof;

Reproduction 2.3 is a left view thereof;

Reproduction 2.4 is a right view thereof;

Reproduction 2.5 is a top view thereof;

Reproduction 2.6 is a bottom view thereof;

Reproduction 2.7 is a front perspective view thereof; and

Reproduction 2.8 is a back perspective view thereof.
